GAS LIFT STARTING VALVE

Filed March 28, 1927

UNITED STATES PATENT OFFICE.

CHARLES C. CARLISLE, OF CHEYENNE, WYOMING.

GAS-LIFT STARTING VALVE.

Application filed March 28, 1927. Serial No. 179,189.

The invention relates to improvements in gas or air lift flow devices by inserting at proper intervals one or more gas lift starting valves as hereinafter described, in the education or in the induction pipe of the gas lift flow device, for the purpose of admitting gas by successive stages into the column of liquid or fluid to be raised or flowed from a well.

The special object sought and attained by this invention is the production of efficient apparatus capable of being placed and operated within wells of customary size and such as are already in existence. This is rendered possible primarily through the special construction of valves and controlling floats herein set forth, whereby they may be of small dimensions yet effective to function under such pressure as may be predetermined and established by suitable adjustment. Other objects are:

First, to provide a means whereby the gas lift may be started to operate at a relatively low gas pressure.

Second, to enable the gas lift to resume operation in case the flow should be checked or retarded long enough to cause it otherwise to cease.

Third, to enable the gas lift flow to be started when the "rock" pressure is not sufficient to permit a gas pressure to be built up in the well to start a flow of liquid through the eduction pipe.

A preferred form of my invention is illustrated in the accompanying drawings, in which:

Figure 1 is a vertical sectional view of a well provided with a casing, and containing a plurality of valves and attendant parts embodying my invention;

Fig. 2, a vertical sectional view of one of the valves and connected parts and of the casing containing the same;

Fig. 3, a horizontal sectional view on the line 3—3 of Fig. 2; and

Fig. 4, an elevation of a portion of the inner pipe of the well on the line 4—4 of Fig. 3, showing said pipe in full lines and the valve and its casing in section.

Referring first to Fig. 1, A designates an

eduction pipe and A' the well casing encompassing said pipe, and provided with a head or cap E which forms a closure for the casing and a support from which the eduction pipe is suspended. The head or cap E is provided with an opening with which is connected an induction pipe F. In the event that the well is drilled through solid rock and a casing be not employed, the head or cap E will be applied to a short length of casing tightly fitted and advisably cemented, into the bore of the well, to seal the same. The suspended pipe A is preferably left open at its lower end, and is advisably provided with holes or openings G at a point a short distance above its lower extremity.

At suitable points in its length, depending upon the depth of the well and the level to which the oil naturally rises in any given case, the pipe A is provided with valves having actuating and control devices of the character illustrated in Figs. 2, 3 and 4. Each such valve is provided with a cover or housing D fashioned to fit snugly against the pipe A, and secured thereto by tap screws or bolts. Each housing D is provided with ports O, O, shown in full lines in Fig. 3 and by dotted lines in Fig. 4, and with vents or openings V through which oil may escape slowly from the valve housing, allowing the valves B, b to remain open for a short period of time after the gas column has passed downward, and until it has reached the next lower valve if there be one, or the normal gas ports below.

Each valve comprises a valve shell 2, here shown of approximately square form, and having a threaded tubular boss or neck M, which in practice is screwed into a suitably tapped opening in the suspended pipe A. The shell 2 has an opening in its upper and in its lower wall, each reamed or beveled at its upper edge to receive respectively a conical upper valve B and similar lower valve b, each carried by a valve rod or stem S extending both above and below the respective valves, as shown in Figs. 2 and 4. The valves B and b are properly spaced to cause their simultaneous seating and unseating. These valves and their seats are shown of like di-

mensions, but may be of relatively different measurement, with consequent differential action, if in any case this be deemed desirable.

The upward extension of valve rod S is encircled by a helical spring C, resting at its lower end upon an upper horizontal arm of a bracket d, conveniently secured to the valve shell 2 and perforated for the passage of the valve stem through it, whereby the bracket is caused to serve also as a guide for said stem. The spring C is compressed to a proper degree by a nut c screwed upon the threaded upper end of the upward extension of the valve stem, with a suitable washer interposed as usual. By varying the adjustment of the nut c, the compression of spring C may be varied as required. A similarly perforated horizontal lower arm of bracket d serves as a guide for the valve stem or rod below the shell 2. The bracket d is shown in Fig. 4 as made in two parts, but it may obviously be made integral. Either arm, or each of the arms, of the bracket may also serve as a stop to limit the rise of valve stem S and the valves and floats carried thereby.

Carried by the valve rod or stem S is a float J, of any suitable construction, here represented as a hollow sheet metal structure, encompassing, and secured in any convenient way to, the valve rod. This float is necessarily of small diameter so as to have proper clearance between the pipe A and the housing D, which latter must clear the casing or wall of the well. Below float J is a cup or receptacle H formed of or lined with, iron, steel, or other substance unaffected by mercury which it is designed to contain. Other dense liquid or a solution of high specific gravity may be employed in lieu of mercury, though mercury is deemed preferable. If a liquid which does not attack or injuriously affect the cup H be employed, the cup may be made of any suitable metal or alloy.

The cup H is formed with an open upper end threaded to receive a sealing cap or plug I, which cap is formed with a depending tubular neck e having at its lower extremity an opening sufficient to permit free movement of the valve rod or stem S through it, but with only sufficient clearance to afford free movement. The neck e is of such length that the annular space about it shall be sufficient to hold the charge of mercury (Hg) contained within the cup H at such times as the cup may be in other than in its upright position, as in handling the same during attachment of the valve casing and the cup to the pipe A, or when the mechanism within housing D is detached from said pipe. The cup H is shown provided with lugs or ears at its upper and lower ends, perforated to receive tap bolts or screws by which it may be secured to the pipe A, said screws or bolts entering tapped holes in said pipe, and the cup H being axially aligned with the valve openings and valves

B, b. Any equivalent or usual mode of attachment may obviously be employed.

Carried by the lower end of the valve stem or rod S is a float L, held between washers at its upper and lower ends, or otherwise held, made adjustable axially by a nut screwed onto the threaded lower end of said valve stem, or in any equivalent way. The float L immersed in mercury or other dense liquid, though of small dimensions, exerts a quite considerable lifting effect upon the valve rod and valves. The small dimensions of the float and its immersion in mercury, permit the float and its containing cup H to be placed within the housing D though the latter projects but a short distance outward from the suspended pipe A. This is a feature of marked importance in a gas lift floating device or starting valve, since the entire valve mechanism with its housing, occupies but small space and does not materially or appreciably reduce the area of the annular space between the suspended pipe and the wall or casing of the well, and hence is capable of application to practically all oil wells now in use.

The floats L and J, which latter is buoyed by the oil entering the housing D when the oil it at a height sufficient so to enter the housing, afford a considerable lifting force tending to unseat valves B and b. This force is supplemented by the spring C, the special utility of which, however, is to afford a simple and convenient means of varying at will the aggregate lifting force to suit the special conditions existing in any particular well. The float L will tend at all times to lift the valve stem and valves, but the float J will lose its lifting effect when the level of the oil in the annular space between the induction and discharge pipes falls below the level of the bottom of the float, and said float will then, to the extent of its weight, tend to draw the valves to their seats. If the compression of spring C be nicely adjusted, each pair of valves B, b, may be caused in turn to seat and close communication between the induction and discharge pipes, the adjustment being such that the opening of the valves will be in sequence, beginning with the topmost valve of the series.

In Figs. 2 and 4 the valves B and b are shown as resting upon their respective seats, hence closing and sealing the shell 2 against the ingress of gas from the space between the induction pipe A' and the eduction pipe A, and precluding the passage of gas through the tubular neck M to the eduction pipe A. This illustrates the condition or adjustment of the valves B, b and the floats J and L in any housing D above the level of the oil in the induction pipe or chamber, due, as indicated to the fact that under such conditions the weight of float J is acting in opposition to float L and spring C, whereas in the housings D below the level of the oil in the induction

- pipe or chamber, the float J, through its buoyancy when surrounded by or immersed in the oil, acts to aid float L and spring C and increase the aggregate lifting effect. As a result, the highest valve mechanism below the upper level or surface of the oil in the annular induction space or chamber, will have its valves lifted or unseated, while all above that level will be seated.
- From the foregoing explanation it will be seen that if gas or air be forced under adequate pressure into the annular space between pipes A' and A, or in other words, into the induction pipe, it will force down the oil in said space until the level of the oil passes below an open valve, since the float J will remain immersed and exert its lifting force until the level of the oil falls below the valve shell 2, thus permitting the gas or air under pressure to enter through the inlet ports of said shell, to pass thence through passage M into eduction pipe A, and to mingle and mix with the oil in said eduction pipe. As the gas or air thus enters the eduction pipe A it will, by reason of its lesser specific gravity and its expansion and breaking up into bubbles, gasify or emulsify the oil from the level at which the gas enters, upward. This will of course expand or upwardly extend the column of oil in the eduction pipe until the top of the column reaches and flows out through the top of said eduction pipe.
- In this way the flow of the oil is started, and the entrance of gas or air into the induction pipe or chamber is advisably made continuous, though brief intermissions may occur without materially interfering with the continuity of action. Such continuing inflow of gas will further depress the level of the oil in the induction chamber and gradually carry the level thereof to a point below the next succeeding valve, if there be another, whereupon the gas will enter the eduction pipe through such valve while the valves above will be automatically closed. This continues until the level of the oil in the induction pipe or chamber is forced below the lowermost valve, and until the gas enters the lower end of the eduction pipe through the perforations in the lower end of the pipe, or if these be not provided, then through the open lower extremity of the pipe. When this point is reached the pressure of the gas or air may be greatly reduced, in some cases to a point as low as one-tenth of the pressure heretofore required in starting the flow and maintaining it until the level of the oil in the induction chamber is lowered to or nearly to the lower end of the eduction pipe.
- As soon as gas begins to pass through the ports of valves B, b in a valve shell 2, the liquid supporting the float in the float chamber formed by the valve housing D and the tubing to which it is attached, begins to drain slowly out through the lower orifice

or vent V, Fig. 2, allowing the float J to settle until the valves B, b close their ports, thus cutting off the gas flow through the gas lift valve.

As stated, the description just given is predicated upon the placing of the valves and their actuating devices in the outer and annular chamber, or between the well casing or pipe A' and the central and suspended pipe A. The valves and the flow of oil may, however, be reversed, that is to say, the suspended central pipe may become the induction pipe, and the outer pipe or well casing may serve as the eduction pipe. In such case the valves would need to be reversed, and might be placed within the inner pipe. This, however, is undesirable because the effective area of the central pipe is materially less than that of the outer pipe.

As above pointed out, the wall of the bored or drilled well, when no casing is employed, constitutes the wall of the outer chamber, and this chamber may constitute either the gas induction or the oil eduction pipe or chamber. Similarly, the suspended central pipe may constitute either the oil eduction or the gas induction pipe, and the term "pipe" as used in the claims is to be understood as comprehending the bored or drilled well, when no casing is employed, and the casing when such casing is used. In other words, the uncased well and the well casing are the well-known equivalents in this art and for the purposes of pressure-fluid lift or flow-starting devices.

The purpose of housing D is two-fold: first, to protect the valve and floats, particularly when placing the pipe within the well or well casing or removing it therefrom; and second, to prolong the period during which the descent of the floats and consequently the seating of the valve or valves takes place. This gradual seating is due to the facts that the opening at the lower end of the housing is quite small, and that liquid escaping from the housing will escape somewhat slowly while the level of the oil or other liquid in the space between the inner pipe and the wall or casing of the well may fall quite rapidly. The larger openings O at the upper end of the housing, as shown in Figs. 3 and 4, permit the rapid filling of the housing when the oil or liquid reaches their level, and provide a passage for gas between the inside and the outside of said housing.

I have shown and described two means for counterbalancing the valve, valve stem, and float J, to wit, the mercury-buoyed float L and the spring C. In practice, the float L is in some instances omitted; in others, the spring C has been omitted; and in still others, both said float L and spring C have been omitted, it being found that if the float J be of proper buoying capacity the device is

operative with either counterbalancing device, or without either the float L or the spring C.

I claim:

- 5 1. A pressure-fluid oil-flowing apparatus of the character described, comprising a pressure-fluid induction pipe; an oil eduction pipe; a passage affording communication between said pipes; a valve controlling 70 said passage; a spring tending to unseat said valve; and a float in the induction pipe, connected with the valve stem, and tending to seat or unseat the valve as oil in said pipe falls below or rises to float-buoying level.
- 10 2. A pressure-fluid oil-flowing apparatus of the character described, comprising a pressure-fluid induction pipe; an oil eduction pipe; a passage affording communication between said pipes; a valve controlling said 75 passage; a spring tending to unseat said valve; a float in the induction pipe, connected with the valve stem, and tending to seat or unseat the valve as oil in said pipe falls below or rises to float-buoying level; and means 80
- 15 25 for adjusting the effective force of said spring.

3. A pressure-fluid oil-flowing apparatus of the character described, comprising a pressure-fluid induction pipe; an oil eduction 30 pipe; a passage affording communication between said pipes; a valve controlling said passage; a spring tending to unseat said valve; a mercury-buoyed float acting in conjunction with said spring; and a second float 35 in the induction pipe, connected with the valve, and serving to supplement the valve-unseating action of the spring and the mercury float when the oil in the induction pipe is at a level to lift said float, but acting in opposition to the spring and the mercury 40 float when the oil falls below said second float.

4. A pressure-fluid oil-flowing apparatus of the character described, comprising two 45 pipes arranged one within the other; a passage affording communication between said pipes; a valve controlling said passage; and a float device tending normally to open said valve, said device comprising a float receptacle provided with a sealing cap having a 50 downwardly extending tubular neck provided with a passage for the stem of said valve, a float within said receptacle carried by the valve stem, a dense liquid contained 55 within said receptacle and serving to buoy said float and partially counterbalance the valve, the space encompassing the depending neck of the sealing cap being sufficient to contain the entire liquid charge of the receptacle when said receptacle is inverted or 60 thrown from its normal vertical position of use, and a second float carried by said stem and adapted to be raised and lowered by and in consonance with the rise and fall of liquid 65 within the space between the pipes.

5. In combination with the wall or casing of a well having a cap or closure at its upper end, a pipe passing through said cap and depending therefrom within the well or casing; a housing carried by said pipe and provided 70 with openings permitting communication between its interior and the annular well space encompassing the pipe; a valve shell within said housing, having a passage connecting its interior with the interior of the pipe and provided with a valve seat; a valve movable to and from said seat for permitting or preventing, according to adjustment, communication between the interior of said pipe and the interior of the housing; a stem carried 75 by said valve; and a float within said housing carried by said stem, and serving when lifted by the rise of liquid within the housing to unseat said valve, and when lowered through fall of said liquid to seat the valve and close 80 communication between the valve shell and the interior of the pipe.

6. A pressure-fluid liquid-flowing apparatus of the character described, comprising two concentric pipes arranged one within the 90 other; a housing carried on the exterior of the inner pipe and provided with openings affording communication between its interior and the annular space between the pipes; a gas valve within said housing controlling 95 communication between said pipes and having a stem extending to a float receptacle; a float receptacle containing a dense liquid; a float within the receptacle, carried by the valve stem and buoyed by said liquid; a closure for said float receptacle serving to seal 100 said receptacle against egress of the float-buoying liquid; and a second float carried by said stem within the housing, adapted to be raised and lowered by and in consonance with 105 the rise and fall of liquid within said housing.

7. In a pressure-fluid liquid-flowing apparatus of the character described, comprising two concentric pipes arranged one within 110 the other; a housing carried by the inner pipe and provided with openings affording communication between its interior and the annular space between the pipes; a valve within said housing, controlling communication 115 between said pipes and provided with a stem; and a valve-opening mechanism comprising a float connected with said stem, a liquid-containing chamber within which the float is placed, mercury within said chamber serving to buoy said float and counterbalance the valve, a closure for said chamber adapted to prevent escape of mercury, and a second float carried by said stem within the housing, adapted to be raised and lowered by and 120 in consonance with the rise and fall of liquid within said housing.

8. In combination with the wall or casing of a well having a cap or closure at its upper end, a pipe passing through said cap and 125
